UNITED STATES PATENT OFFICE.

FREDERICK H. OGDEN, OF NEWARK, NEW JERSEY.

ROTARY STEAM-ENGINE.

1,269,735.

Specification of Letters Patent. Patented June 18, 1918.

Application filed March 11, 1916. Serial No. 83,533.

To all whom it may concern:

Be it known that I, FREDERICK H. OGDEN, a citizen of the United States, residing in the city of Newark, in the county of Essex and State of New Jersey, have invented certain new and useful Improvements in Rotary Steam-Engines, of which the following is a full, clear, and exact description, such as will enable others skilled in the art to 10 which it pertains to make, construct, and use the same, reference being had to the accompanying drawings, and to numerals of reference marked thereon, forming a part of this specification.

15 This invention relates to rotary steam engines, and consists in mechanisms whereby the act of starting, stopping, and reversing the engine is performed by a simple movement of the throttle, with lightning-like 20 rapidity and perfect control at any speed, without shock or jar; as the inertia of the mass of steam is cushioned against the pressure at the boiler.

The objects of my invention are to increase 25 the simplicity of the construction and operation of the engine, by decreasing the number of parts of which the usual engine is composed; by lessening or avoiding the necessity for adjustment of the various 30 parts, and by increasing the convenience in manipulation of the engine. To this end, I have made many changes in this engine from similar engines described in previous 35 patents; all with the object of increased efficiency.

Enumerating the different features of my invention, I would say that firstly, I construct the central rotating member or hollow shaft with two pistons attached, and providing 40 said pistons each with an increased piston area. The hollow shaft is provided with eduction ports communicating with the engine casing to permit the spent steam to be exhausted therethrough, and out 45 through the base into the atmosphere. Secondly, my invention consists in the novel construction of the balanced sliding steam valve, with three ports accurately spaced, which is movable end-wise or horizontally 50 within the central rotating member or shaft to which the two pistons are attached, and over a stationary steam sleeve, which is provided with a plurality of ports registering 55 with a steam chamber and the ports in said sliding valve, so that a forward movement

of the throttle, which is secured to the balanced-steam valve, moves said valves and brings a port in the valve in line with a port in one of the pistons through which the steam travels to the steam chamber. 60 Continued movement of the engine cuts off the supply of steam and the piston continues to move on expansion until the related port in the other piston is in line with another port in the valve. At this point, 65 the pistons trade functions and the spent steam is exhausted through the reverse port in the idle piston to the hollow shaft, and thence through the eduction-ports in the shaft to the engine casing out into the atmosphere. A backward movement of the 70 throttle brings the valve ports in line with the reverse ports in the pistons, performing the same operations for the reverse as for the forward movement.

75 The invention comprises certain special constructions, combinations and arrangements of parts, as hereinafter set forth.

In the drawings, in which like numerals of reference indicate corresponding parts, 80 throughout,

Figure 1 represents a side elevation of my improved reversible rotary engine, in which the balanced sliding steam valve is employed.

Fig. 2 represents a transverse, vertical section taken on lines 2—2 of Fig. 3.

Fig. 3 represents a longitudinal, vertical central section of the entire engine.

Fig. 4 represents a central longitudinal 90 section of my improved balanced steam valve and stationary steam sleeve employed in the reversing type of engine.

Fig. 5 represents a transverse vertical section taken on line 5—5 of Fig. 4, looking in 95 the direction indicated by the arrow.

Fig. 6 represents a central longitudinal section, partly in elevation, of the one-way stationary steam valve as employed in the non-reversing type of engine.

Fig. 7 represents a transverse vertical section of the same, taken on line 7—7 of Fig. 6, and looking in the direction indicated by the arrow.

Fig. 8 represents a transverse vertical section of my improved device, of the non-reversing type, in which the one-way stationary valve is employed.

Fig. 9 represents a fragmentary view of the central rotating member or shaft, with 110

the pistons secured thereon, and the one-way stationary steam valve located in the central rotating member or shaft.

5 Figs. 10, 11 and 12 represent front, side and rear elevations of my improved pistons.

Fig. 13 represents an end elevation of the same; and

10 Fig. 14 represents a transverse section of the pistons taken on lines 14—14 of Fig. 12, and looking in the direction indicated by the arrow.

15 Referring to the drawings, the four essential working parts of the engine consist of a central rotating member or hollow shaft 1, to which two pistons 2 are rigidly secured in any desired and convenient manner, these two constituting one working part, and the three conical rolling cylinder heads 3, constituting the remaining three parts, 20 the rolling cylinder heads being each provided with pockets or cavities to allow the pistons to pass through. Each member revolves upon its own center of revolution by gearing to a pinion secured on the central shaft. All of the aforesaid four parts 25 revolve in the same plane and are entirely gyroscopic in motion, thus insuring against noise and vibration.

30 The engine casing consists of a housing 4, provided with a circumferential annular chamber 5, containing the two diametrically-opposite pistons 2, adapted to travel therein. As previously stated, the pistons 2 are properly secured by means of a key or otherwise to the central hollow rotating member or shaft 1, which shaft is supported in suitable bearings 6 and 6' formed on the covers 7 and 8 of the engine casing, so that travel of the pistons 2 will cause rotation of said 40 shaft 1. Arranged in the corners of an equilateral triangle at points across the annular chamber 5 and pathway of the pistons 2, are the three conical rolling cylinder heads 3, each rolling cylinder head being 45 provided with a gear-wheel 9, designed to engage with a gear wheel 10, secured to the rotating member or shaft 1, whereby said rolling cylinder heads 3 are caused to turn to present the pockets or cavities 11 to allow 50 the pistons to pass through.

55 At equidistant points through the walls of the covers 7 and 8 of the engine casing, are arranged tubular extensions 12, each provided with a suitable cap or cover 13, said tubular extensions 12 having secured therein suitable ball-bearings 14 in which the ends 15 of the rolling cylinder heads 3 are secured.

60 The bearings 6 and 6' of the covers 7 and 8 are also provided with suitable caps or covers 16 and 17, said bearings having secured therein suitable ball bearings 18, in which the ends of the central rotating member or shaft 1 revolve. The cover 17 also 65 acts as a valve guide, to which the throttle

19 is pivoted, as clearly indicated in Figs. 1 and 2 of the drawings, one end of the throttle being conveniently secured to one end of the balanced steam valve 20, as in the reversing type of engine, in any desired or 70 convenient manner. The stationary steam sleeve 21 is conveniently secured to the end of the cover 17 by means of a suitable union 22. This construction will permit the ready removal of the balanced steam valve 20 from 75 the interior of the rotating member or shaft 1, by simply removing the cover 17 with its attached stationary sleeve 21, and also permits at the same time the ready removal of the hollow shaft 1.

80 The stationary steam sleeve 21, as indicated in Figs. 2 and 4 of the drawings, is a hollow, tubular member provided at its open end with preferably an integral collar 23, by means of which, it, together with 85 the union 22, is secured to the end of the cover 17, and near its closed end, said stationary steam sleeve is provided with a plurality of ports 24 registering with the steam chamber 25 of the balanced-sliding steam valve 20. The balanced-steam valve 20 is provided with a central bore 26, designed to receive the stationary steam sleeve 21, and with which said steam valve 20 has sliding engagement.

90 The closed end of the sliding steam valve 20 is provided with a tubular extension 27, designed to have sliding engagement with the reduced portion of the hollow shaft 1 with which the steam valve 20 has sliding 100 engagement.

95 The sliding steam valve 20 is provided with three ports 28, accurately spaced, communicating with the steam chamber 25, and the hollow shaft 1 is also provided with 105 ports 29 registering with ports 30 formed in the piston 2, so that a forward movement of the throttle, which is secured to the balanced steam valve, brings a port in the valve in line with the port in one of the 110 pistons, through which the steam travels to the steam chamber 5.

115 In the reversing type of engine, as illustrated in Fig. 3 of the drawings, a pair of reverse ports 31 are also employed in the piston, and indicated in dotted lines, through which the spent steam is exhausted through similar ports 32 in the hollow shaft, also shown in dotted lines, and thence through the eduction ports 33 to the engine casing 120 out into the atmosphere, as indicated by the arrows in Fig. 2 of the drawings.

125 In order to provide the pistons 2 with an effective increased piston area, the same are formed with a serrated surface, as clearly indicated in Figs. 9, 11, 12 and 13 of the drawings.

130 In Figs. 6, 7, 8 and 9, I have illustrated a one-way valve 35, primarily designed to be used in the non-reversing type of engine,

said valve being provided with a central longitudinal bore 36, and which is rigidly secured to the end of the cover 17, in any desired or convenient manner, the closed end 5 of which is also provided with a tubular extension 37, designed to have engagement with the reduced portion of the hollow shaft 1, in a similar manner as the tubular extension 27 of the sliding valve 20 is illustrated 10 in Fig. 2 of the drawings. The one-way valve 35 is also provided with three ports 38, accurately spaced, communicating with ports 39 of the hollow shaft 1, see Fig. 8 of the drawings, which ports 39 register 15 with ports 40 formed in the piston 2, through which the steam travels to the steam chamber 5.

The pistons employed in the non-reversing type of engine are only provided with a 20 single set of ports 40, as distinguished from the pistons employed in the reversing type of engine, which are provided with two sets of ports, namely, ports 30 and 31.

Experience has demonstrated that the organization above described is a highly efficient one, and while the device described is the preferred embodiment of my present invention, I do not care to restrict myself to the exact details of construction, combination 25 and arrangement herein set forth, it being obvious that minor variations thereof, not involving the exercise of invention, may be made by any skilled mechanic, and such departures from what is herein described 30 and claimed, I consider within the scope and terms of my claims.

Having thus described my invention, what I desire to secure by Letters Patent is:—

1. In a rotary engine, an annular chamber, pistons adapted to travel in said annular chamber, cylinder heads located within said chamber, being provided with cavities to allow the pistons to pass through, a central rotating member or hollow shaft extending 40 through said chamber and to which said pistons are secured, a stationary steam sleeve located within said central rotating member or hollow shaft, provided with ports, and a sliding-balanced steam valve 45 surrounding said steam sleeve located in said central rotating member, said balanced steam valve having sliding engagement with said stationary steam sleeve and central rotating member and further provided with 50 ports designed to register with corresponding ports in the central rotating member and said steam sleeve, to introduce steam in the annular chamber to drive said pistons around within said annular chamber.

60 2. In a rotary engine, an annular chamber, pistons adapted to travel in said annular chamber, cylinder heads located within said chamber, being provided with cavities to allow the pistons to pass through, a central 65 rotating member or hollow shaft ex-

tending through said chamber and to which said pistons are secured, a stationary steam sleeve located within said central rotating member or hollow shaft, provided with ports, and a sliding-balanced steam valve 70 surrounding said steam sleeve located in said central rotating member, said balanced steam valve having sliding engagement with said stationary steam sleeve and central rotating member and provided with an annular steam chamber, and further provided with ports 75 designed to register with said annular steam chamber and with corresponding ports in the central rotating member and said steam sleeve, to introduce steam in the annular chamber to drive said pistons around within said annular chamber.

3. In a rotary engine, an annular chamber, pistons adapted to travel in said annular chamber, cylinder heads located within 80 said chamber, being provided with cavities to allow the pistons to pass through, a central rotating member or hollow shaft extending through said chamber and to which said pistons are secured, a stationary steam sleeve 85 located within said central rotating member or hollow shaft, provided with ports, and a sliding-balanced steam valve surrounding said steam sleeve located in said central rotating member, said balanced steam valve having sliding engagement with said stationary steam sleeve and central rotating member and provided with an annular steam chamber, and further provided with 90 ports designed to register with said annular steam chamber and with corresponding ports in the central rotating member and said steam sleeve, to introduce steam in the annular chamber to drive said pistons around within said annular chamber.

4. In a rotary engine, an annular chamber, pistons adapted to travel in said annular chamber, cylinder heads located within said chamber, being provided with cavities to allow the pistons to pass through, said pistons being provided with an increased piston area, a central rotating member or hollow shaft extending through said chamber and to which said pistons are secured, a balanced-steam valve provided with a steam chamber located within and having sliding engagement with said central rotating member or hollow shaft, a stationary steam sleeve located within said sliding-balanced steam valve, all of said parts being 110 provided with corresponding ports to introduce steam in the annular chamber to drive said pistons around within said annular chamber.

5. In a rotary engine, an annular chamber, pistons adapted to travel in said annu- 115

lar chamber, cylinder heads located within said chamber, being provided with cavities to allow the pistons to pass through, said pistons being provided with an increased 5 piston area, a central rotating member or hollow shaft extending through said chamber and to which said pistons are secured, a balanced-steam valve provided with a steam chamber located within and having sliding 10 engagement with said central rotating member or hollow shaft, a stationary steam sleeve located within said sliding-balanced steam valve, all of said parts being provided with corresponding ports to introduce 15 steam in the annular chamber to drive said pistons around within said annular chamber and means for moving said balanced-steam valve horizontally within said central rotating member and over said stationary 20 steam sleeve.

6. In a rotary engine, an annular chamber, pistons adapted to travel in said annular chamber, cylinder heads located within said chamber, being provided with cavities to 25 allow the pistons to pass through, a central rotating member or hollow shaft extending through said chamber and to which said pistons are secured, means secured to the cylinder heads and operatively connected with 30 means secured to the hollow shaft for rotating said cylinder heads and permitting the pistons to pass therethrough, a stationary steam sleeve located within said central rotating member or hollow shaft, provided with 35 ports, and a sliding-balanced steam valve surrounding said steam sleeve located in said central rotating member, said balanced steam valve having sliding engagement with said stationary steam sleeve and central ro-

tating member and further provided with 40 ports designed to register with corresponding ports in the central rotating member and said steam sleeve, to introduce steam in the annular chamber to drive said pistons around within said annular chamber. 45

7. In a rotary engine, an annular chamber, pistons adapted to travel in said annular chamber, cylinder heads located within said chamber, being provided with cavities to allow the pistons to pass through, a central rotating member or hollow shaft extending through said chamber and to which said pistons are secured, means secured to the cylinder heads and operatively connected with means secured to the hollow 50 shaft for rotating said cylinder heads and permitting the pistons to pass therethrough, a stationary steam sleeve located within said central rotating member or hollow shaft, provided with ports, and a sliding-balanced 55 steam valve surrounding said steam sleeve located in said central rotating member, said balanced steam valve having sliding engagement with said stationary steam sleeve and central rotating member and provided with 60 an annular steam chamber, and further provided with ports designed to register with said annular steam chamber and with corresponding ports in the central rotating member and said steam sleeve, to introduce 65 steam in the annular chamber to drive said pistons around within said annular chamber. 70

This specification signed and witnessed this 7th day of March, 1916.
